Attn:

UNITED STATES PATENT OFFICE.

HANS KNÖRER, OF NUREMBERG, GERMANY, ASSIGNOR TO A. W. FABER "CASTELL" BLEISTIFT-FABRIK A. G., OF NUREMBERG, GERMANY.

DESIGN FOR A PENCIL CONTAINER.

Application filed February 15, 1929, Serial No. 30,071, and in Germany October 18, 1928. Term of patent 7 years.

To all whom it may concern:

Be it known that I, HANS KNÖRER, residing at Nuremberg, in the county of Bavaria, Germany, have invented a new, original, and ornamental Design for a Pencil Container, of which the following is a specification, reference being had to the accompanying drawing, forming part thereof.

The figure is a perspective view of my pencil container showing my new design.

I claim:

The ornamental design for a pencil container as shown.

HANS KNÖRER.
